COMBINED HEADREST AND ADJUSTABLE
SUNSHADE UNIT

Lee J. Stair, 531 Main St., Clinton, Tenn.

Filed June 15, 1960, Ser. No. 60,963

Term of patent 14 years

(Cl. D15—8)

FIG. 1

Figure 1 is a rear perspective view of a combined headrest and adjustable sunshade unit, showing my new design, and

Figure 2 is a front perspective view thereof.

I claim:

The ornamental design for a combined headrest and adjustable sunshade unit, substantially as shown.
